UNITED STATES PATENT OFFICE.

CHRISTY A. VANE, OF ST. LOUIS, MISSOURI, ASSIGNOR TO NATIONAL AUTOMOBILE DEALERS' ASSOCIATION, OF ST. LOUIS, MISSOURI, AN ASSOCIATION OF ILLINOIS.

DESIGN FOR AN EMBLEM, SIGN, BADGE, BUTTON, OR ARTICLE OF SIMILAR NATURE.

61,218.

Specification for Design.

Patented July 11, 1922.

Application filed April 14, 1922. Serial No. 1,747. Term of patent 14 years.

To all whom it may concern:

Be it known that I, CHRISTY A. VANE, a citizen of the United States, residing at St. Louis, in the county of St. Louis City and State of Missouri, have invented a new, original, and ornamental Design for Emblems, Signs, Badges, Buttons, or Articles of Similar Nature, of which the following is a specification, reference being had to the accompanying drawing forming part thereof, in which a badge embodying my new design is shown in elevation.

I claim:

The ornamental design for an emblem, sign, badge, button, or article of similar nature, as shown.

CHRISTY A. VANE.
